CHAIR FOR CELLO PLAYERS

Application filed September 10, 1928. Serial No. 304,861.

cello to assist in firmly holding it in a correct position.

5 His right leg is slightly withdrawn, backwardly, and lowered, this allowing him to depress the bow so as to conveniently reach the right hand strings of the cello without interference with his right knee,—the shortening of the side 5^a permitting the player to lower his right leg so that the bow 10 is drawn over it.

10 The instrumentalist is, therefore, very comfortably seated, but not only this, he has opportunity to rest his back against the chair back 2, except at such times as he may prefer 15 to lean forwardly to execute some difficult passage in his musical score.

15 Another advantage accruing from the use of this improved chair is the ability of the player to retain a substantially constant sitting position throughout the execution of a 20 musical composition.

20 In many musical pieces there are certain periods of rest in which the cellist is idle. Sitting in the ordinary chair he must slide 25 back and forth, first to play his instrument and then to rest against the chair back. This is tedious for the player.

25 In my chair the cellist can draw his instrument toward the back of the chair, with 30 in the depression 6 sufficiently to allow him to remain in an easy and comfortable body position without constantly shifting, first ahead and then back, as he does with the conventional type of chair.

35 Having described the superior features and advantages of my improved cellist's chair, what I claim and desire to secure by Letters Patent is:—

40 A chair comprising seat-supporting legs, a seat superimposed on said legs having sides of relatively different lengths, and a depression formed in said seat, between said sides, extending rearwardly to a point in a plane disposed backwardly of the front end of the 45 shorter of the two said sides.

45 In testimony whereof I affix my signature.
JOSEPH FRANZOSA.
